E. W. Buxford -

Attorney

UNITED STATES PATENT OFFICE

EDWARD E. HILL, OF INDIANAPOLIS, INDIANA

ADAPTER FOR CASKET LAMPS

Application filed July 14, 1928. Serial No. 292,775.

My invention relates to devices for illuminating caskets, and more particularly to an adapter designed to be used in conjunction with my casket lamp, such as I have illustrated in my Patent No. 1,672,317 dated June 5, 1928, and it is an object of the invention to provide means enabling my casket lamp to be used in a house not provided with electricity, by utilizing a portable source of electricity, 10 as for example, a conventional storage battery, and the addition of a combined plug and socket which screws into the socket in my lamp, and has a reduced bayonet socket for the reception of a miniature bulb, as for example a 6 volt, 21 candle power automobile bulb; all as will be hereinafter more particularly described and claimed.

Referring to the accompanying drawings, which are made a part hereof and on which 20 similar reference characters indicate similar parts,

Figure 1 is a perspective illustrating the application of my invention,

Figure 2, a diagrammatic view, and

25 Figure 3, a longitudinal section through the adapter plug.

In the drawings reference character 10 illustrates a casket upon which is supported my improved casket lamp 11, above referred to, having a plug 12 at its extremity, which may be screwed into the conventional house socket for furnishing the source of energy for lighting the lamp 11. As a substitute for the source of power just described, I provide a conventional storage battery 13 to the poles of which are attached the terminals 14 from a socket 15 into which the plug 12 may be secured. The power thus furnished is insufficient to operate the ordinary 110 volt lamp, 40 and I therefore provide a lamp of the same capacity as the storage battery (usually a 6-8 volt, 21 candle power lamp), and in order to provide a receiving socket so that the same may be supported in the lamp 11, I provide 45 a structure such as I have shown in Figure 3, which comprises a screw plug 16 having an enlarged corrugated knurled head 17 by means of which it may be screwed into the lamp socket. The screw plug is hollowed out at 18 and into such hollowed portion is inserted a

bayonet socket of the proper size to receive the miniature bulb, not shown, such socket being formed of an insulating sleeve 19 fixed upon an insulating body 20 which carries spaced contacts 21 which engage the contacts on the bulb. The screw plug is provided with a metal tip 22 and a metallic sleeve 23 to which are secured conductors 24 and 25 which form electrical connection between the contact elements and the sleeve and tip. The body 20 is secured in the screw plug 16 by a plastic composition 26 composed of whiting, plaster and glue.

With this construction, my casket lamp may be readily used in a home which is not provided with electricity, and at a very small cost, 65 which is the rental price of a storage battery.

It will be obvious to those skilled in the art that various changes may be made in my device without departing from the spirit of the invention, and I, therefore, do not limit myself to what is shown in the drawings and described in the specification, but only as set forth in the appended claims.

Having thus fully described my said invention what I claim as new and desire to secure by Letters Patent, is:

1. A device of the class described comprising a screw plug hollowed at the rear, a reduced bulb socket carried by said screw plug set in the hollowed portion of the screw plug, a plastic composition securing said reduced socket in position, a pair of longitudinally disposed contact elements projecting rearwardly into the sleeve, a metal tip on the plug, a metallic sleeve about the plug, and connections from said contact elements to said tip and sleeve, substantially as set forth.

2. A device of the class described comprising means for operating an electric casket lamp by a storage battery comprising a connection between the storage battery and the lamp, an adapter for accommodating a reduced bulb to said lamp including a screw plug hollowed at the rear, a reduced bulb socket carried by said screw plug set in the hollowed portion of the screw plug, a plastic composition securing said reduced plug in position, a pair of longitudinally disposed contact elements projecting rearwardly into

the sleeve, a metal tip on the plug, a metallic sleeve about the plug, and connections from said contact elements to said tip and sleeve, substantially as set forth.

5 In witness whereof, I have hereunto set my hand at Indianapolis, Indiana, this twelfth day of July, A. D. nineteen hundred and twenty-eight.

EDWARD E. HILL.
